(57) **CLAIM**

The ornamental design for a comestible segregator, as shown and described.

DESCRIPTION

FIG. 1 is an isometric view of a comestible segregator showing my new design.

FIG. 2 is a front elevation view thereof.

FIG. 3 is a right side elevation view thereof.

FIG. 4 is a left side elevation view thereof.

FIG. 5 is a rear elevation view thereof.

FIG. 6 is a top plan view thereof.

FIG. 7 is a bottom plan view thereof; and,

FIG. 8 is an exploded isometric view thereof.

The claimed design is directed to the appearance of the segregator in its assembled state and is shown disassembled in FIG. 8 for the purpose of clarifying design aspects of the assembled segregator that are not apparent from other views.
